UNITED STATES PATENT OFFICE.

NEVVENS N. NUNN, OF MAPLEWOOD, MISSOURI, ASSIGNOR TO THE ALMETAL MANUFACTURING COMPANY, OF MAPLEWOOD, MISSOURI, A CORPORATION OF MISSOURI.

WASHING-MACHINE.

1,351,486.

Specification of Letters Patent. Patented Aug. 31, 1920.

Application filed December 23, 1918. Serial No. 267,966.

To all whom it may concern:

Be it known that I, NEVVENS N. NUNN, a citizen of the United States, residing at Maplewood, St. Louis county, Missouri, have invented a certain new and useful Improvement in Washing-Machines, of which the following is a full, clear, and exact description, such as will enable others skilled in the art to which it appertains to make and use the same, reference being had to the accompanying drawings, forming part of this specification.

My invention relates generally to motor-driven washing machines of the type employing a vertically reciprocating plunger carrying on its lower end a pounder or clothes engaging member, and my invention relating more particularly to a clutch mechanism which is interposed between the motor-driven shaft of the machine and the reciprocating plunger and said clutch being specifically designed for throwing the reciprocating shaft or plunger into or out of operation and which clutch, when disconnected, being arranged so as to stop the reciprocating shaft or plunger at the termination of its upward stroke or movement.

My improved clutch mechanism is particularly applicable for that type of washing machine which includes a container, a hinged cover therefor, a rod or plunger mounted for reciprocatory movement through said cover, and a pounder or clothes engaging member carried by the lower end of said plunger. In this particular type of machine, the relative sizes of the container and the pounder or clothes engaging member are such that the hinged cover for the container can be swung into full open position only when the plunger is at its highest point of movement within the container, for if an attempt is made to swing the hinged cover into open position with the pounder in its lowered position, the edge of said pounder will strike against the side wall of the container, with the result that the parts are bent or broken. To overcome this objection, I propose to provide a clutch mechanism which will be effective in stopping the reciprocating rod which carries the pounder at the end of its upward movement and in which position the cover can be readily swung into open position without contact between the pounder and container.

The principal object of my invention is

to provide a relatively simple clutch mechanism which can be readily shifted from one position to another and which clutch is positive in action and very effective in performing its intended functions.

With the foregoing and other objects in view, my invention consists in certain novel features of construction and arrangement of parts, hereinafter more fully described and claimed, and illustrated in the accompanying drawings, in which—

Figure 1 is an elevational view of the upper portion of a washing machine, and showing my improved clutch mechanism applied thereto.

Fig. 2 is a plan view of the clutch and showing the operating lever thereof.

Fig. 3 is a vertical section taken approximately on the line 3—3 of Fig. 2 and showing the clutch in open or disengaged position.

Fig. 4 is a section similar to Fig. 3 and showing the clutch in closed or engaged position.

Fig. 5 is an enlarged detail section taken lengthwise through the center of the clutch members.

Fig. 6 is a cross section taken approximately on the line 6—6 of Fig. 4.

Fig. 7 is a cross section taken on the line 7—7 of Fig. 4.

Fig. 8 is an enlarged cross section taken approximately on the line 8—8 of Fig. 2.

Referring by numerals to the accompanying drawings, which illustrate a practical embodiment of my invention, 10 designates the container of a motor-driven washing machine, 11 the hinged cover therefor, 12 a rod which is arranged for reciprocatory movement through the central portion of the cover 11, 13 the pounder or clothes engaging member carried by the lower end of said rod 12, 14 a fly wheel, 15 a pitman arranged between said fly wheel and the reciprocating rod 12, and 16 a motor-driven shaft, all of these parts being well-known in the art and forming no part of my invention.

Fixed in any suitable manner on the cover 11 to one side of the centrally arranged shaft 12 is a stand or bracket 17, the upper end thereof being provided with horizontally aligned bearings 18 and 19 in which are mounted aligned shaft members 20 and 21 respectively. The outer end of shaft 20 has a suitable driving connection with

the upper end of motor-driven shaft 16 or parts driven thereby, and the outer end of shaft 21 carries the fly wheel 14. The adjacent or inner ends of the shafts 20 and 21 are connected and maintained in alinement by an axially disposed pin or stud 22, the same being fixed to either one of the shafts 20 and 21, and loosely seated in the other.

Fixed on shaft 20 adjacent to bearing 18 10 is a collar 23 and mounted for sliding movement upon shaft 20 adjacent to this collar is a second collar 24. This collar 24 is held to rotate with shaft 20 by means of a pin 25 which passes through said shaft and 15 which occupies diametrically arranged slots 26 formed in said collar.

Interposed between the collars 23 and 24 are compression springs 27, the tendency of which is to force collar 24 away from collar 23. Collar 24 is provided with a clutch face 28 from which projects a lug 29.

A relatively short sleeve 30 is mounted upon a key or feather 30^a seated in the inner end of shaft 21 so as to rotate with and 25 slide lengthwise upon said shaft, and formed in said sleeve is an annular groove 31. The inner end of this sleeve 30 is provided with a clutch face 32 which includes a recess 33, the latter being adapted to receive lug 29. The opposite end of sleeve 30 is provided with a notch or recess 34 which is adapted to receive a pin 35, the latter projecting inwardly from bearing 19.

Fixed to the bearings 18 and 19 and serving 35 as a cover for the clutch mechanism just described is an inverted U-shaped plate 36 on top of which to one side of the center is fulcrumed a short hand lever 37. Formed through the cover plate and concentric with 40 the axis of the hand lever is an arcuate slot 38, and seated in the hand lever and projecting through this slot is a pin 39, the lower end of which carries a roller 40 and the latter occupying groove 31 in sleeve 30.

Seated in the underside of hand lever 37 45 is a spring-pressed pin 41, the lower end of which is adapted to engage in either one of a pair of recesses 42, the latter being formed in the top of cover plate 36. (See Figs. 2 and 8.) This spring-pressed pin is effective in yieldingly retaining the hand lever in either one of its set positions, and which positions determine the engagement or disengagement of the clutch.

The relative positions of the pitman 15, pin 35 and notch 34 are such that when the parts are properly assembled and when the pin 35 occupies notch 34, the reciprocating rod 12 will be held at its upper limit of 50 movement or in the position illustrated in Figs. 1 and 3. Under such conditions, it will be understood that the clutch is disengaged and to effect such disengagement, the hand lever 37 is shifted to its limit of movement toward the righthand, as seen in Fig.

2, and such movement is transmitted to said sleeve through pin 39 carrying roller 40 which operates in groove 31.

Spring-pressed pin 41 carried by the hand lever engages in the righthand one of the 70 recesses 42 thereby yieldingly retaining said hand lever in its shifted position.

To close the clutch or engage the parts thereof in order to transmit rotary motion from the main driving shaft 16 to shaft 20 75 and thence to shaft 21 which carries fly wheel 14 to which pitman 15 is connected, the hand lever 37 is moved to its lefthand limit of movement, which action shifts sleeve 30 toward the lefthand, and by so 80 doing, brings clutch face 32 into coöperation with clutch face 28 and when collar 24 rotates to the proper position, lug 29 will engage in notch or recess 33, thus locking the two parts of the clutch together with the result that the rotary motion of shaft 20 will be transmitted to shaft 21 and parts carried thereby.

During the latter part of the movement of sleeve 30 toward collar 24 or when the high portions of the clutch faces engage with each other, collar 24 will be moved toward the lefthand a short distance against the resistance offered by spring 27 and this yielding movement is effective in permitting the two parts of the clutch to come into engagement with each other gradually and without sudden jerking movements, which latter, it will be understood, would tend to strain parts of the mechanism.

Inasmuch as the reciprocating rod 12 is stopped at its upper end of its travel, the pounder or clothes engaging member 13 carried by said rod will, when the latter stops, occupy a position in the top of the container 10 and when so positioned, said pounder will clear the upper edge of the container 10 when the cover 11 is swung into open position.

A clutch of my improved construction is 110 comparatively simple, can be easily and cheaply manufactured, is positive in action and is very effective in use.

It will be readily understood that minor changes in the size, form and construction 115 of the various parts of my improved device may be made and substituted for those herein shown and described, without departing from the spirit of my invention, the scope of which is set forth in the appended claims. 120

I claim:

1. In a clutch of the class described, a pair of rotatably mounted alined shafts, clutch members mounted to rotate with and move lengthwise upon said shafts, a lever 125 provided with locking pins for shifting one of said clutch members lengthwise upon its shaft and locking said member in position, yielding pressure means for resisting the movement of the other one of the clutch 130

members away from the manually operable clutch member, and a bearing provided with a pin for engaging the first mentioned clutch member.

- 5 2. In a clutch of the class described, a suitable bracket provided with bearings on each end, a pair of rotatably mounted alined shafts, a guide pin mounted in the end of one of the shafts and recessed in the adjacent end of the other shaft, a relatively fixed clutch member mounted on the first mentioned shaft, a sliding clutch member mounted on the other shaft, said fixed clutch member being provided with suitable cushioning means, the aforesaid bracket having a suitable cover plate provided with an arcuate slot and a pair of recesses spaced apart, a shift lever mounted on said cover plate provided with a depending pin and 15 roller mounted thereon, and a pair of spring-pressed pins, the roller adapted to en-

gage the slidable clutch member through the slot and the spring pressed pins engaging the recesses as set forth.

3. In a clutch of the class described, a suitable bracket provided with bearings on each end, a pair of rotatably mounted alined shafts, a guide pin mounted in the end of one of the shafts and recessed in the adjacent end of the other shaft, a relatively fixed clutch member mounted on the first-mentioned shaft, a sliding clutch member mounted on the other shaft, means for shifting the sliding member, a suitable recess in the sliding member, and a pin projecting from the bearing adjacent said sliding member, said pin engaging the recess when the clutch members are separated.

In testimony whereof I hereunto affix my signature this 16th day of December, 1918.

NEVVENS N. NUNN.
